UNITED STATES PATENT OFFICE

109,035

DESIGN FOR A BOTTLE OR SIMILAR ARTICLE

Sing Chun, Honolulu, Territory of Hawaii

Application December 17, 1937, Serial No. 73,690

Term of patent 7 years

To all whom it may concern:

Be it known that I, Sing Chun, a citizen of the United States of America, residing in the city of Honolulu, in the county of Honolulu, in the Territory of Hawaii, have invented a new, original, and ornamental Design for a Bottle or Similar Article, of which the following is a specification, reference being had to the accompanying drawing, forming part thereof.

In the drawing:

Fig. 1 is a front elevation of a bottle or similar article, showing my new design.

Fig. 2 is a side elevation thereof.

I claim:

The ornamental design for a bottle or similar article, as shown.

SING CHUN.
